UNITED STATES PATENT OFFICE.

FREDERICK H. HOFFMANN, OF JERSEY CITY, NEW JERSEY.

STROPPING-MACHINE.

1,214,034.

Specification of Letters Patent. Patented Jan. 30, 1917.

Application filed March 13, 1913. Serial No. 753,904.

To all whom it may concern:

Be it known that I, FREDERICK H. HOFFMANN, a citizen of the United States, residing in Jersey City, in the county of Hudson and State of New Jersey, have invented certain new and useful Improvements in Stropping-Machines, of which the following is a full, clear, and exact description.

This invention relates to improvements 10 in razor stropping machines generally, and more particularly to stropping machines for safety razor blades which are usually made of thin material and which it is consequently more or less difficult to satisfactorily strop or sharpen without the employment of some specific means for properly guiding the blade on the strop in the reciprocatory movement which is necessary in the stropping process.

20 The object of the present invention is to provide a stropping machine which will be extremely durable and which will at the same time be simple in construction, so that it may be economically produced.

25 A further object of my invention is the production of a stropping machine for razor blades wherein but few movable parts are employed, the arrangement of those parts being such that they will coöperate in 30 a manner which will insure positive and efficient operation of the device.

My invention further contemplates a razor blade stropping machine in which the mechanism employed for reciprocating the 35 blade holder is in part formed integral with the frame of the device, so that the possibility of displacement of the parts and the consequent necessity for adjustments are reduced to a minimum.

40 I shall now proceed to describe my invention with reference to the accompanying drawings and then point out with more particularity the elements of novelty therein in the appended claims.

45 In the drawings: Figure 1 is a plan view from the bottom of my improved razor stropping machine; Fig. 2 is a longitudinal sectional view of my device taken on the line A—A of Fig. 1; Fig. 3 is a transverse 50 view of the front end of the frame; and

Fig. 4 is a similar view of the opposite side of the portion of the frame shown in Fig. 3.

Referring now to the drawings in detail in which like characters of reference are employed to designate similar parts throughout the several views, I provide a frame preferably of rectangular configuration, comprising a front plate 7 and a rear plate 8 which are connected by the parallel rods 9 and 10 as shown in Fig. 1. Each of said plates 7 and 8 is provided with a centrally located elongated slot 11 through which the rod 12, carrying the blade holder 13 as shown, extends, the end of said rod contiguous to the rear plate 8 of the frame being threaded or otherwise adapted to have rigidly secured thereto the handle 14. Each of the said plates 7 and 8 has a rack 15 and 16 formed integral therewith and preferably at the top portion thereof (see Fig. 70 4), the teeth of each of said racks being arranged to mesh with the pinions 17 and 18 respectively which are rigidly secured to the ends of the blade carrier 13 rotatably mounted on the rod 12, so that the reciprocation of the rod will simultaneously rotate or rock said carrier 13 in the manner and for the purposes which will herein-after be more fully explained. As will be noted, each of said elongated slots 11 has 75 formed integral therewith on its lower side an inwardly directed flange 19, providing a bearing surface for the rod 12, which is held against longitudinal movement within said slots 11 by the pinions 17 and 18 and 80 the plate 20 rigidly secured to one extremity thereof and which rides upon the outer surface of the plate 7, and the abutment or shoulder 20^a which is similarly secured to said rod and likewise rides upon the outer 85 surface of the other plate 8.

Mounted on the outer surface of the plate 7 adjacent to each end thereof, are the lugs or projections 21 in which is rigidly mounted a rod 22, said rod passing through an 90 aperture 23 in the boss 24 formed on the reciprocating plate 20, said boss 24 being normally capable of unrestricted longitudinal movement on said rod 22. Mounted on the rod 22 are a pair of coil springs, the 95 100

opposite ends of one spring 25 bearing respectively against one of the projections 21 and the boss 24, the other spring 26 being similarly arranged with respect to the other projection 21 and the opposite side of said boss 24. These springs under normal conditions serve to maintain the blade carrier 13 in its central inoperative position, as shown in Figs. 1, 2 and 3.

10 It will be obvious from the structure hereinbefore described that in the employment of my invention the strop 27 is passed through the frame over each of the rods 9 and 10 and under the blade-carrier rod 12.

15 The blade holder 13 is rotatably mounted on this latter rod and is preferably formed with two jaws of resilient material as shown between which the razor blade is inserted, the tension of the material serving to hold the blade firmly within the carrier. In the stropping operation, as is well known, the stropping machine is moved to and fro or reciprocated on the strop 27 by means of the handle 14. By this movement the blade-carrier 13 is rocked by means of the pinion 17 and 18 meshing with the racks 15 and 16 on the frame of the machine, the initial movement of the handle in one direction rocking the carrier 13 until the rod 12 abuts

20 one end of each of the elongated slots 11, which serves to bring one edge of the blade 28 in the carrier 13 into effective engagement with the contiguous surface of the strop, (see Fig. 4) the continued movement of the stropping machine in the same direction effecting the stropping of that edge of the blade. The movement of the machine in the reverse direction will similarly bring the opposite edge of the blade into engagement with the stropping surface. It will be observed that in the reciprocation of the machine on the strop 27, the coil springs 25 and 26 will be alternately contracted, the expansion thereof serving to assist and make positive the reciprocatory movement of the blade carrying member within the frame of the machine.

25 While I have described my invention with regard to the specific details of structure herein shown, it is obvious that the structure may be varied in minor details without departing from the spirit and scope of my invention as set forth and claimed herein.

30 Having thus described my invention, what I claim as new herein and desire to secure by Letters Patent is:

35 1. A stropping machine for razor blades comprising a frame formed with a pair of oppositely positioned elongated slots, a blade carrier movably mounted within said slots, a rack formed integral with each end of said frame and adjacent to each of said slots, a pair of pinions mounted on said

blade carrier in mesh with said racks, means for reciprocating said blade carrier, whereby said racks and said pinions will coöperate to impart a rocking motion to said blade carrier, a rod mounted exteriorly of said frame and means freely movable thereon and adapted to alternately engage and coöperate with said reciprocating means to facilitate the movement of said blade carrier in the stropping operation.

2. A stropping machine for razor blades, comprising a frame formed with a pair of oppositely positioned elongated slots, a blade carrier movably mounted within said slots, a rack formed integral with said frame adjacent to each of said slots, a pinion rigidly mounted on said blade carrier in proximity to each end thereof each pinion being in mesh with its contiguous rack, and means in engagement with said blade carrier for reciprocating the same within said slots, whereby said racks and said pinions will serve to rock the same; and a pair of spiral springs mounted exteriorly of said frame and adapted to alternately engage with one end of said blade carrier, said springs being adapted to assist the movement of said blade carrier within said slots.

3. A stropping machine for razor blades, comprising a frame formed with a pair of oppositely positioned elongated slots, a blade carrier movably mounted within said slots, a rack formed integral with said frame adjacent to each of said slots, pinions mounted on said blade carrier and in mesh with each of said racks, a rod positioned transversely of said frame and a pair of spiral springs loosely mounted on said rod and adapted to contact with a portion of said blade carrier to normally maintain said blade carrier in the blade inserting position, and means for reciprocating said blade carrier to oscillate the same, the oppositely disposed spiral springs being alternately compressed upon the reciprocation of said blade carrying member, the inactive spring being out of contact with said blade carrier when its opposite is compressed, whereby the expansion of the compressed spring will serve to assist in the reciprocatory movement of said blade carrier.

4. A stropping machine for razor blades, comprising a frame formed with a pair of oppositely positioned elongated slots, one of said frame members having oppositely disposed ears formed thereon, a rod positioned within said ears, a blade carrier movably mounted within said slots, a rack formed integral with said frame adjacent to each of said slots, pinions rigidly mounted on said blade carrier and in mesh with each of said racks, and a pair of spiral springs mounted on said rod and in engagement with said ears and a portion of said blade car-

rier, and means for reciprocating said blade carrier, whereby said springs will be alternately compressed, the expansion of the compressed spring serving to return the blade carrier to its normal blade inserting position.

5 In witness whereof I have hereunto set

my hand in the presence of two subscribing witnesses.
